Primary Examiner — Michael Pratt*(74) Attorney, Agent, or Firm* — Boyle Fredrickson, S.C.**CLAIM**

The ornamental design for a canted firearm optic support post, substantially as shown and described.

DESCRIPTION

FIG. 1 is a perspective view a canted firearm optic support post according the present invention;

FIG. 2 is top plan view of the optic support post shown in FIG. 1;

FIG. 3 is an elevation view of a right side of the optic support post shown in FIG. 1;

FIG. 4 is an elevation view of a front side of the optic support post shown in FIG. 1;

FIG. 5 is a bottom plan view of the optic support post shown in FIG. 1;

FIG. 6 is an elevation view of a left side of the optic support post shown in FIG. 1; and,

FIG. 7 is an elevation view of a rear side of the optic support post shown in FIG. 2.

The broken lines represent environmental structure and show portions of the design that form no part of the claimed design.
